UNITED STATES PATENT OFFICE.

AMY FLORENCE BROWNING, (NOW BY MARRIAGE A. FLORENCE B. ROTHE,) OF DEVON,
PENNSYLVANIA.

PATTERN.

1,158,976.

Specification of Letters Patent.

Patented Nov. 2, 1915.

Application filed January 20, 1910. Serial No. 539,028.

To all whom it may concern:

Be it known that I, AMY FLORENCE BROWNING, (now by marriage A. FLORENCE B. ROTHE,) a citizen of the United States, 5 residing at Devon, in the county of Chester and State of Pennsylvania, have invented a new and useful Pattern, of which the following is a specification.

My invention relates to improvements in 10 patterns.

It is especially adapted for use in cutting what are known as "princesse" undergarments, that is, one-piece undergarments of non-elastic or unstretchable material, ex- 15 tending substantially to or below the knees and fitting closely to the contour of the figure at the waist line and over the hips.

The object is to provide a standard pattern by the use of which in cutting garments 20 of the character described, the fit of the garments will be materially improved and the cloth for the same economically utilized.

My invention comprises a pattern the 25 length of the garment to be cut, extending from the front to a point substantially to the rear of a vertical line passing from the armpit over the wearer's hip, at which point the contraction of the female figure at the 30 waist relatively to the lower portion of the body is most marked, and a coöperating pattern section or sections for use with the main pattern section. The said pattern sections are suitably proportioned to insure the 35 smooth, close fit and graceful hang of the garment cut therefrom.

Referring to the drawings: Figure 1 is a 40 large full length pattern section. Fig. 2 is a coöperating pattern section. Fig. 3 is an additional coöperating pattern section. Fig. 4 is a pattern for the buttoning flaps. Fig. 5 is a front view of a figure dressed in a 45 combined corset cover and drawers cut from my pattern. Fig. 6 is a rear view of a figure dressed in a similar garment cut from my pattern. Fig. 7 is a pattern for a closed yoke. Fig. 8 is a front elevation of a 50 combined corset cover and drawers, the yoke of the same cut from a pattern section similar to that shown in Fig. 7.

Similar numerals refer to similar parts 55 throughout the several views.

The undergarment shown in Fig. 8 is the subject of Patent No. 1,084,071 granted to me July 30, 1912, on application filed January 20, 1910.

It will be understood that the pattern sections shown in Figs. 1 and 2 may be employed twice in cutting the cloth for the garment. The section shown in Fig. 3 need only be employed once, although if preferred the portion to the left of dotted line 31 may be employed as a separate pattern section. 31 indicates the line upon which the pattern section is folded when the section is cut.

Referring to the pattern section of Fig. 1, and to the garments shown in Figs. 5 and 6 which are assumed to have been cut from the patterns shown in Figs. 1, 2 and 3, the garment section corresponding in outline to the said pattern section comprises the full length of the garment and extends from the median line in front, around the hip and beneath the armpit, to line 7 of Fig. 6. As means for conforming the garment section to the contour of the figure at the waist and over the hips there is provided in the pattern section, in addition to the inwardly curving side margins 6 and 24, and the sections 22 and 23 indicating a pair of darts, a longitudinally disposed opening 18 extending upwardly from the bottom of the pattern section and narrowing near the bust line in front. This opening indicates a section of material to be cut away on lines 19 and 20 curving as indicated, at the waist line in opposite directions toward the side margins. Line 21 in Figs. 5 and 8 indicates the meeting edges of the cloth when brought together in the completed garment.

Referring now to the coöperating pattern sections shown in Figs. 2 and 3, each of margins 33, and 26 and 11 narrow at the waist line, as indicated, to coöperate with the main pattern section and duplicate pattern sections in conforming to the contour of the figure. While the portion of the section shown in Fig. 3 to the right of line 31 and the pattern section of Fig. 2 may be formed in a single piece if desired, the form shown, in which both pattern sections terminate approximately the waist line and separate back and seat pieces are formed, is preferred.

Line 7, Fig. 6, indicates the points of union of the garment sections cut from the three pattern sections, while line 11 in said figure indicates the point of union at the opposite edge of the garment section corresponding to the pattern section of Fig. 2 and a duplicate garment section. The said

duplicate section is shown connected at its opposite edge to a duplicate of the garment section conforming to the pattern section of Fig. 1. It will be understood that the garment sections conforming to Figs. 1 and 2 will be joined from the crotch, 9, immediately below the short curves 8 and 27, to the bottom of the garment, thus forming the drawers leg. It will also be understood that the narrowed upper end of the garment section conforming to the pattern section of Fig. 2, having the narrowed end portion 25, will be joined to the garment section conforming to the pattern section of Fig. 3 on lines 28 and 29 of said figures, see line 30 of Fig. 8.

The oval recessed portion 17 of Fig. 1 indicates the material to be removed to form an armhole. Strap-shaped extensions 13 and 14 flanking said recessed portion are of course duplicated in the garment section and are there secured together on lines 15 and 16. The curve at the top of the garment section conforming to 32 of Fig. 3, the short curve at the top of the outer strap-shaped extension and the curving upper extension, conforming to 12, of the main garment section, thus form the neck opening of the garment.

It will thus be seen that by the employment of the pattern sections described the material may be so cut as to insure a smooth and close fit at the waist and hips and to hang in a straight fold from the waist to the hem of the drawers. The large garment section may be cut economically from a width of material by arranging its pattern section and the cloth so that the edges of the cloth extend relatively to the pattern section, in direction parallel to dotted line 5. The sagging of the completed garment in the back due to the cut of the fabric on the bias at margin 24, will be prevented since margin 26 of the pattern section shown in Fig. 2 may be cut straight with the weave of the fabric from a point approximate the waist line to the bottom of the pattern section. Margin 20, coöoperating with biased margin 19, may also be cut substantially straight with the weave throughout the greater part of its extension. At the same time, a minimum of separate parts and seams, either vertical or horizontal, will thus be secured by the employment of my improved pattern, the customary vertical seam over the hip, at which point the contour of the female figure at the waist is most marked, being omitted altogether and darts preferably provided at this point. Plaits or gathers in the back of the garment will also be unnecessary.

The pattern section of Fig. 7 may be employed when it is desired to provide a closed yoke as shown in Fig. 8, in which case the yoke may be sewed to the garment above

tucks 41 with extensions 49 flanking the neck opening. 38 indicates the line upon which the section is folded when it is cut.

Fig. 4 shows a pattern section for one of the buttoning flaps shown in Fig. 5 and a pattern for one of those shown in Fig. 8, the pattern for the former extending down to dotted line 34 only, and the pattern for the latter from end to end of the drawing. In a garment similar to that shown in Fig. 5 the section may be folded on dotted line 35 and edges 36 and 37 sewed to edge 6 of the main section, a similar garment section being sewed to the corresponding side of a similar main section. In a garment similar to that shown in Fig. 8 the garment section would preferably be folded on line 35 and then on dotted line 40, equidistant from the two ends of the section, sewed to the front edge of the main section from 39 to 10 in Fig. 1 and up the corresponding edge of the duplicate section, the two ends of the folded flap section being sewed together.

It will be obvious that if desired my improved pattern may be outlined upon cloth and sold as an article of commerce, as well as in the form of a paper pattern which is the preferred way.

What I claim is:—

1. A pattern for undergarments, comprising a section substantially the full length of the garment, said section narrowing near the waist line, widening toward the bottom and extending from a point in the front to a point in the rear short of or removed from the median line, and a coöoperating pattern section narrowing near the waist line and widening toward the bottom at one side, the first mentioned section adapted when applied to the fabric to be cut, to have its rearwardly disposed side margin at a bias to the weave of the fabric, the other pattern section adapted readily to permit the fabric section to be cut below the waist line at its more forwardly disposed side, substantially straight with the weave, as and for the purpose specified.

2. A pattern for undergarments, comprising a section substantially the full length of the garment, said section narrowing near the waist line, widening toward the bottom and extending from a point in the front to a point in the rear short of or removed from the median line, and two shorter pattern sections converging toward the waist line, one terminating approximately thereat at the top and widening toward the bottom at one side, the other terminating approximately thereat at the bottom, the longest of said pattern sections adapted when applied to the fabric to be cut, to have a side marginal portion substantially straight with the weave of the fabric and an oppositely disposed side marginal portion at a bias to said weave, and the first mentioned of the two shorter pat-

tern sections adapted to permit the corresponding fabric section to be cut below the waist line at its more forwardly disposed side, substantially straight with the weave, 5 as and for the purpose specified.

3. A pattern for undergarments, comprising a section substantially the full length of the garment and extending approximately from the median line in front to a point 10 short of or removed from the median line in the rear, said section wider at the bottom than at the top, narrowing near the waist line and provided with an opening extending from the bottom of the pattern section 15 upwardly and narrowing near the bust line, a substantial portion of the more rearwardly disposed margin of said opening being substantially vertically disposed and the oppositely disposed marginal portion of said 20 opening being inclined thereto, and a co-operating pattern section narrowing at the waist line and widening toward the bottom at one side, the first mentioned pattern section adapted when applied to the fabric to 25 be cut, to have a side marginal portion and the last mentioned side marginal portion of

said opening substantially straight with the weave of the fabric, and an oppositely disposed side marginal portion at a bias to said weave, the other pattern section adapted 30 readily to permit the corresponding fabric section to be cut below the waist line at its more forwardly disposed side, substantially straight with the weave, as and for the purpose specified. 35

4. A pattern for undergarments, comprising a section substantially the full length of the garment, said section narrowing at the waist line and extending from a point in the front to a point in the rear short of or removed from the median line, and a co-operating pattern section between said point in the rear and said median line, said last mentioned section having a relatively narrow extension near the waist line and widening 40 therefrom toward the bottom at its more rearwardly disposed side, substantially as described. 45
